UNITED STATES PATENT OFFICE.

JAMES L. COLVIN, OF SCRANTON, PENNSYLVANIA.

FOOT-POWER BRAKE.

Application filed November 24, 1920. Serial No. 426,270.

To all whom it may concern:

Be it known that I, JAMES L. COLVIN, a citizen of the United States, residing at Scranton, in the county of Lackawanna and State of Pennsylvania, have invented certain new and useful Improvements in Foot-Power Brakes; and I do hereby declare the following to be a full, clear, and exact description of the invention, such as will enable other skilled in the art to which it appertains to make and use the same.

This invention relates to new and useful improvements in brakes and more particularly to the mode of operating a brake on a railway car or the like. The main object of this invention is the provision of means for operating a brake by foot pressure whereby the brakeman can readily operate the brake by engaging his foot with a suitable foot treadle and pressing downwardly upon the same whereby to rotate the brake shaft and apply the brake. Suitable means is also provided for retaining the brake shaft against rotation to unwind the brake, said means being readily released when it is desired to release the brake.

Another object of the present invention is the provision of a foot operating brake mechanism which is to be used in replacing the old and well known form of hand operated brake and is arranged in such a position with respect to the car that during the operation of the device, the person operating the same will have free use of both hands to hold himself in position upon the end platform of the car while operating the brake whereas in the old hand operated style, the operator only had the use of one hand to retain himself in position and sometimes had to use both hands in operating the brake.

With the above and other objects in view, the invention consists in the novel features of construction, combination and arrangement of parts hereinafter more fully set forth, pointed out in the claim and shown in the accompanying drawings in which:

Figure 1 is an elevation of a portion of one end of a railway car illustrating the application of my improved brake mechanism;

Fig. 2 is a front elevation of the same;

Fig. 3 is a similar view showing the different positions of the foot treadle which operates the brake shaft and the pivoted

pawl which retains the shaft against movement after the brake has been applied; 55

Fig. 4 is a detail elevation illustrating the relative positions of the pawl and handle for operating the same when engaging the ratchet; 60

Fig. 5 is a similar view illustrating the positions assumed by the pawl and handle when out of engagement with the ratchet;

Fig. 6 is a detail perspective view of the handle member which operates the pawl; 65

Fig. 7 is a detail perspective view of the pawl;

Fig. 8 is a side elevation of the arm upon which the foot treadle is mounted; and,

Fig. 9 is a detail perspective view of the pawl carried by the arm and which engages the ratchet for rotating the main gear to impart movement to the brake shaft. 70

Referring now more particularly to the drawings accompanying this application the numeral 1 indicates the body of a well known type of railway car having attached to one end thereof the vertically spaced supports 2 upon which is mounted a platform 3, said platform being supported in position by means of the brackets 4. It will be noted that in arranging the uprights 2 in position upon the ends of the cars, it is preferred to have them arranged adjacent the step members 5 so that the brakeman can readily ascend the steps 5 onto the platform 3. 75

The operating mechanism is supported in position upon the platform 3 by means of an angular bracket 6, the horizontal portion of which rests upon the upper face of the shelf 3 and secured thereto in any suitable manner. The brake shaft 7 extends up through the platform 3 and the horizontal portion of the bracket 6 and is provided upon its upper end with a beveled gear 8 80 adapted to mesh with a similar gear 9 which is mounted upon a shaft 10 supported by the bracket 6 and disposed in such position that the teeth thereof will engage the gear 8 to 90 rotate the brake shaft upon rotation of the gear 9. 100

In order to impart rotation to the gear 9 an arm 11 is mounted upon the shaft 10 and connected with the gear 9 in any suitable manner, said arm being provided with a bearing 12 whereupon the same will readily swing upon the shaft 10 for rotating the gear 9. The outer end of the arm is pro- 105

vided with a foot piece 13 adapted to be engaged by the foot of the operator to press the same downwardly from the position illustrated in Fig. 2 to the position illustrated in full lines in Fig. 3. In order to impart movement to the gear 9, a pawl 14 is mounted for pivotal movement upon a pin 15 carried by the arm 11 and as the end of the arm 11 which carries the foot piece 13 is moved downwardly from the position illustrated in Fig. 2, the pawl 14 will engage the ratchet teeth 16 formed upon the periphery of the gear 9 and rotate the said gear so that the teeth on the side portion of the gear 9 will engage with the gear 8, thus imparting a rotary movement to the shaft 7.

The pawl 14 is provided with an outwardly projecting arm 17 which in its normal operating position lies parallel with the arm 11, the weight of said arm engaging the pawl 14 with the ratchet teeth 16 upon downward movement of the arm 11 to impart a rotary movement to the gear 9. In order to return the arm 11 to its normal position illustrated in Fig. 2, a suitable weight 18 is attached to the end of the arm 11 opposite the foot piece 13, so that when the operator's foot is removed from the foot piece 13 upon completing the downward movement of the arm 11, the weight 18 will return the arm to its normal position illustrated in Fig. 2 and also in dotted lines in Fig. 3. In order to disengage the pawl 14 from the ratchet teeth 16 upon upward movement of the arm 11, a plate 19 is attached to the upright portion of the bracket 6, the outer end of said plate being substantially reduced to provide a finger 20 which is offset with respect to the plate 19 and is adapted to engage the projected side portion 21 of the pawl 14 upon the upward movement of the arm 11 whereby to disengage the pawl from the ratchet teeth 16, this movement being clearly illustrated in dotted lines in Fig. 3. It will be noted from the construction of the pawl 14 that the point which engages the ratchet teeth 16 is substantially thicker than the main body of the pawl to provide the projecting side portion 21 which is adapted to be engaged by the finger 20 to force the pawl out of engagement with the ratchet teeth 16 upon the upward movement of the arm 11.

In order to retain the gear 9 against backward movement after the brake has been applied, or during the application of the brake, a pivoted pawl 22 is mounted upon the shaft 23 carried by the upright portion of the bracket 6, the movement of said pawl being controlled by means of the lever 24. The lever 24 is provided at its inner end with a sleeve 25 having a cutaway portion 26 provided with inclined faces 27 arranged upon each side of the shaft 23 and adapted to engage the inclined side walls of the

shaped recess 28 formed within the lower face of the pawl 22. It will be noted that the body of the pawl 22 is slightly larger in thickness than the engaging portion so that sufficient material is provided for to form the recess 28 to receive the portion 26 on the lever 24.

In Fig. 3 I have illustrated in full lines, the pawl 22 engaged with the ratchet teeth 16 to prevent backward movement of the gear 9 and in this position, one of the inclined faces 27 is engaged with one of the inclined faces of the recess 28 so that the weight of the lever 24 will tend to retain the pawl into engagement with the ratchet teeth 26 as it will be noted that when the pawl is in this position, the lever 24 will be disposed in an inclined position upon one side of the shaft 23. In dotted lines in Fig. 3, I have illustrated the pawl 22 disengaged from the ratchet teeth 16 and the lever 24 disposed in an inclined position opposite to the position shown in full lines when the pawl is engaged, the weight of the lever thus retaining the pawl out of engagement with the ratchet teeth 16 so that the brake shaft will be permitted to rotate in a direction to release the brake. In order to prevent the lever 24 from swinging beyond a predetermined position, a pin 29 is arranged in the upright portion of the bracket 6 to provide a stop to thus limit the swinging movement of the lever. It will be noted that the lever 24 is provided at its outer end with a handle portion 30 whereby this lever can be readily operated to engage or disengage the pawl 22 with the teeth 16.

From the above description taken in connection with the accompanying drawing, it will be readily apparent that when it is desired to apply the brake, the brakeman will position his foot upon the foot piece 13 and by pressing downwardly upon the outer end of the arm 11, the pawl 14 will engage the ratchet teeth 16 and tend to rotate the gear 9 which in turn will rotate the shaft 7 to apply the brake. In order to retain the gear 9 against backward movement, the lever 24 is swung to the position illustrated in full lines in Figs. 2 and 3 so that the pawl 22 will engage the ratchet teeth 16 and retain the gear 9 against backward movement when the arm 11 is returned to its normal position illustrated in Fig. 2 so that further strokes of the arm 11 can be carried out until the shaft 7 has been rotated sufficiently to apply the brakes. When it is desired to release the brakes, the brakeman can either manipulate the lever 24 with his hand or by giving the same a kick with his foot release the pawl 22 from the ratchet 16. Should he be unable to disengage the pawl 22 from the ratchet 16 in the manner described above, the outer end of the arm 11 will be compressed so as to rotate the gear

9 sufficient to permit the pawl 22 to be
readily released from the ratchet 16 so that
when the arm 11 is released, the brake shaft
will rotate in a direction to release the
5 brake.

If so desired, suitable means may be pro-
vided for enclosing the mechanism described
above to protect the same from the weather
and also to prevent displacement of the
10 parts, said means being in any suitable
form of housing, if desired.

What I claim is:

In a brake comprising a supporting
bracket, a brake shaft, a bevelled gear car-
ried by the end of said shaft, a stub shaft
15 disposed at right angles to the brake shaft,
a bevelled gear mounted upon the stub
shaft and engaging the gear on the brake

shaft, and a ratchet on the periphery of the
second gear; a double armed lever pivoted 20
upon the stub shaft and normally disposed
in an inclined position relative the hori-
zontal with one end above the shaft, means
carried by the lever for engagement with
the ratchet whereby to rotate said gears 25
upon the application of pressure to the
upper end of said lever, means carried by
the end of said lever arm for returning the
same to its normal position upon release of
the pressure, means engaging said ratchet 30
to prevent backward movement of the gears
and a finger carried by the supporting
bracket to contact and disengage the ratchet
engaging means.

In testimony whereof I affix my signature.
JAMES L. COLVIN.
